UNITED STATES PATENT OFFICE.

REINHOLD A. NORLING, OF AURORA, ILLINOIS, ASSIGNOR TO INDEPENDENT PNEUMATIC TOOL COMPANY, OF CHICAGO, ILLINOIS, A CORPORATION OF DELAWARE.

REVERSIBLE DRILL THROTTLE.

Application filed April 6, 1922. Serial No. 550,190.

This invention relates to reversible throttle valves for pneumatic tools and more particularly for pneumatic drills.

One object of my invention is to make the taper in the bore of the tubular valve member and the bearing surface thereon on the stem relatively slight so that the end areas of the air passage chambers in the valve member are substantially the same and thus have very little back pressure on the valve member during the flow of the air therethrough, and furthermore require the use of but a very light spring to hold the valve member on the taper and thus make the valve member turn freely and easily.

Another object of my invention is to make this taper just enough to take up the wear between the parts and further to prevent the valve from sticking on the taper by means of an adjustable sleeve on the stem and bearing on that end of the valve member opposite the spring.

A further object of the invention is to provide a safety lock for the valve member while in position running the drill or tool forward and thus prevent the valve member being accidentally turned in position to reverse the drill.

A further object of the invention is to improve the construction of reversible throttles as heretofore made by making the device more simple in construction and provide it with fewer and more substantial parts.

The invention consists further in the matters hereinafter described and more particularly set forth in the appended claims.

In the accompanying drawings—

Fig. 1 is a longitudinal vertical sectional view of a throttle valve mechanism constructed in accordance with my invention and taken approximately on line 1—1 of Fig. 5;

Fig. 2 is a transverse vertical sectional view taken on line 2—2 of Fig. 1, and showing the outside valve member in the position indicated by the full lines in that figure;

Fig. 3 is a similar view of the same parts when the outside valve has been turned into the position indicated by the dotted lines in Fig. 1;

Fig. 4 is a similar view of the same parts when the valve member is turned while the safety lock is on;

Fig. 5 is a top plan view of said throttle valve device with the drill casing in horizon-

tal section to show the air actuated pistons 55 and their controlling valves;

Fig. 6 is an elevational view of the throttle stem;

Fig. 7 is a fragmentary longitudinal vertical sectional view of the safety lock;

Figs. 8 and 9 are transverse vertical sectional views taken on lines 8—8 and 9—9, respectively, of Fig. 1; and

Fig. 10 shows a detail of the safety lock.

In the drawings, 1 indicates a drill casing, in which are housed and operate the pneumatically driven parts by which rotary motion is imparted to the spindle of the tool. In the form of drill shown, these parts include air actuated pistons 2, 2 to which the supply of live or compressed air is controlled by valves 3, 4, as illustrated in Fig. 5.

The drill casing 1 has two outwardly extending handles 5, 6 arranged on opposite sides thereof, as usual in tools of this general character, and one of these handles, namely the one 5, is provided with the throttle valve mechanism of my invention for controlling the supply of motive fluid to the drill and for reversing the operation of the same.

The handle 5 comprises a stem 7 having its inner end secured in a boss 8 on the drill casing by a clamp nut 9. At the outer end of the stem 7 is a nipple or cap 10, by means of which an air supply hose (not shown) is attached to the handle 5. The forward portion of said stem 7 is provided with a longitudinal air supply passage 11 opening at one end into the nipple 10 and at the other end into a cross-passage 12. This is between the ends of the stem and opens outward through the same on opposite sides thereof, as shown in Fig. 1. The portion of the stem 7 between the cross-passage 12 and the drill casing 1

is provided with two longitudinal air passages 13, 14 opening, respectively at their inner ends into the air chambers 15, 16 in the drill casing 1, as shown in Fig. 1. These chambers communicate with the cylinders of the pistons 2, 2 through the valves 3, 4 in accordance with the design of drills of this kind. The outer ends of the passages 13, 14 open outward through the stem 7 on opposite sides thereof adjacent the cross-passage 12 and are in the plane of the latter.

Communication between the cross-passage 12 and the respective air passages 13, 14 is con-

trolled by a tubular throttle valve member 17 rotatively mounted on the exterior of the stem 7 over the cross-passage 12 and the adjacent ends of the passages 13, 14, as shown in Fig. 1. As there illustrated, the stem 7 has a slightly tapered portion 18 where the valve member 17 is mounted and the bore of said valve member has a complementary taper to fit the same on the stem. This taper 10 of the stem 7 extends beyond the bearing of the valve member 17 to the beginning of the external screw threads 19 on said stem 7, as shown in Figs. 1 and 6. This is to allow the valve member 17 to move up on the taper 15 18 as the parts wear and thus insure a leak proof joint between them at all times.

Surrounding the stem 7 on the threaded portion 19 is an internally threaded split sleeve 20 bearing against the opposed end 20 of the valve member 17 and forming an end thrust bearing therefor. For clamping the sleeve 20 on the threaded portion 19, there is a split clamp collar 21 surrounding the sleeve 20, as shown in Figs. 1 and 5. Said 25 collar 21 has outwardly projecting ears or lugs 22, 22 at its split or severed ends to receive the clamp bolt 23. In assembling the parts, the valve member 17 is slipped over the outer end of the stem 7 and the valve and stem both being tapered, the valve is allowed to go up on the stem only so far, then the threaded sleeve 20 is screwed up against it and clamped in place by the collar 21. This 30 will prevent the valve member 17 from moving any further on the taper and keep it from sticking on being turned.

Rotatably mounted on the portion of the stem 7 between the nipple 10 and valve member 17 is a grip sleeve 24. This is provided 40 at its inner end with two oppositely arranged tongues 25, 25 entering similarly arranged slots 26, 26 in the adjacent end of the valve member 17 so that the latter may be rotated by turning the grip sleeve 24. A coil spring 45 27 surrounds the stem between the valve member 17 and the grip sleeve 24 to exert pressure on the valve member 17 in a direction to hold it up on the tapered portion 18 and against the sleeve 20. The valve member 17 and grip sleeve 24 are both counter-bored out to receive the spring 27 and are provided with inwardly extending parts for the ends of the spring to engage, as shown in Figs. 1 and 7. Said spring 27 has a tendency 50 to push the grip sleeve 24 away from the valve member 17, and to resist this the cap or nipple 10 has a shoulder 28 for the outer end of the grip sleeve to bear against, as shown in Fig. 1.

60 To prevent the valve member 17 from being accidentally turned to reverse the drill while running forward, I provide a safety lock as follows.

The valve member 17 at its end adjacent 65 the grip sleeve 24 is provided with an in-

wardly extending key 29 in the space between two radial stop shoulders 30, 30^a on the stem 7, as shown in Figs. 1 to 4 and 6. Surrounding the valve member 17 at the key 29 is a ring 31 internally grooved to receive 70 a flat split spring band 32. Said clip has a normal diameter slightly less than the outside diameter of the valve member 17 where the clip fits about the same, and when applied on the valve member must be expanded, thereby causing the clip to have a relatively tight grip on the valve member 17. With the clip located in the groove of the ring 31, the side portions of the ring are on opposite sides of the clip, and thus the ring is held from 75 accidental lateral sliding movement on the valve member 17 by the clip. (See Fig. 10.) The grip of the clip or band 32 is not tight enough, however, to prevent the ring 31 from being manually slid back and forth along 80 the valve member when desired. The ring 31 has a lug or pin 33 extending inwardly through the split in the clip 32 into an elongated slot 34 in the portion of the valve member 17 surrounded by said ring, as shown in 85 Figs. 5 and 7. When the ring 31 is shifted laterally toward the inner end of the slot 34, the pin 33 is brought into the space between the shoulders 30, 30^a and when shifted in the opposite direction the pin 33 is moved out 90 of the space between said shoulders for the purpose to be presently described, the spring band 32 holding the ring in its positions of 95 adjustment.

The mechanism shown and described operates as follows. When running the drill in the reverse direction as when turning the drill spindle to the left, the valve member 17 is in the position shown in full lines in 100 Figs. 1 and 2. In this position, the chamber 17^a of the valve member 17 connects the passages 11 and 13 together through the cross-passage 12 and supplies live air to the piston cylinders through the chamber 15 in the drill casing. The opposite chamber 17^b of the valve member 17 opens the outer end of the passage 14 to the atmosphere for the exhaust, and at this side of the valve member there is a deflector flange 17^c extending toward the 105 drill casing 1 to direct the exhaust away from the operator.

In this position of the parts, the key 29 on the valve member 17 is against the shoulder 30, and the pin 33 on the ring 31 is out of the space between said shoulders to permit turning of the valve member to the full distance between the same, as shown in Fig. 2.

In running the drill forward as when turning the drill spindle to the right, the valve member 17 is turned by the grip sleeve 24 into a position to bring the key 29 against the shoulder 30^a, as shown in Fig. 3. This brings another chamber 17^d of the valve member 17 into the position shown in dotted lines in Fig. 1 and connects the supply passage 11 115 120 125 130

with the passage 14 through the cross-passage 12, and the second exhaust chamber 17^a of the valve member over the outer end of the passage 13 to exhaust the same to the atmosphere. The deflector flange 17^c is then on top of the handle 5 and directs the exhaust toward the drill and away from the operator. In this position of the parts, the supply of air to the drill would be through the passages 11, 12, 14 and drill chamber 16, while the exhaust would be from the drill chamber 15 through the passage 13.

After the valve member 17 has been turned to run the drill forward, the ring 31 is shifted from the position shown in full lines in Figs. 5 and 7 to the position shown in dotted lines in those figures. This brings the pin 33 in the space between the shoulders 30, 30^a, as clearly shown in Fig. 4. Should the grip sleeve 24 be turned, the pin 33 will contact with the shoulder 30 before the valve member 17 reaches reverse position and thus prevent reversing of the drill. In this movement, however, the valve member 17 will be turned far enough to shut off the supply of air to the drill because neither of the chambers 17^a or 17^d are brought into register with any of the handle passages.

The taper between the valve member 17 and stem 7 is very slight, about 1° on the side. This makes the end areas of the air passage chambers of the valve member substantially the same because of the slight difference between the ends of the taper, with the result that there is very little back pressure on the valve member during the flow of air therethrough. Consequently, the valve member 17 turns freely and easily, and moreover a relatively light spring 27 is all that is required to hold the valve member up on the taper. Moreover, the taper being slight prevents such differences in the end areas in the valve chambers as to cause the valve member to be lifted off its seat by the air flowing therethrough.

The sleeve 20 being adjustable toward the valve member 17 prevents the latter from sticking on the taper, yet allows it to come up far enough on the same to prevent leaking. The clamp collar 21 is made separate from the sleeve 20 so that its lugs or ears 22 may be always positioned not to strike the deflector flange 17^c in the turning of the valve member 17. Thus when the sleeve 20 is adjusted, the lugs 22 may be positioned as stated.

The spring band 32 makes an even and smooth tension on the ring 31, and holds it in place, but moves smoothly without sticking and the bore of the ring and outside of the valve member 17 need not be machined closely.

While I have shown and described herein in detail a reversible throttle valve mechanism of my invention, it is of course to be

understood that the details of construction and arrangement of parts may be variously changed and modified without departing from the spirit and scope of my invention.

I claim as my invention:

1. A reversible drill throttle, comprising a stem having a tapered portion between its ends and having supply and drill passages opening outward through said taper, a tubular valve member with a tapered bore fitting the taper of the stem over the open ends of said passages and having inlet and exhaust chambers for reversing the flow of air through the drill passages on turning the valve member, the taper of the stem and that of the bore being complementary and relatively slight so that the end areas of said valve chambers will be substantially the same, a relatively light spring at the smaller end of the taper for holding the valve member up on the same, and an end thrust bearing for the valve member at the larger end of the taper.

2. A reversible drill throttle, comprising a stem having a tapered portion between its ends and having supply and drill passages opening outward through said taper, a tubular valve member with a tapered bore fitting the taper of the stem over the open ends of said passages and having inlet and exhaust chambers for reversing the flow of air through the drill passages on turning the valve member, the taper of the stem and that of the bore being complementary and relatively slight so that the end areas of said valve chambers will be substantially the same, a relatively light spring at the smaller end of the taper for holding the valve member up on the same, and a sleeve adjustable on the stem at the larger end of the taper and forming an end thrust bearing for the valve member.

3. A reversible drill throttle, comprising a stem having a slightly tapered portion between its ends and having supply and drill passages opening outward through said taper, a tubular valve member with a slightly tapered bore fitting the taper of the stem over the open ends of said passages and having inlet and exhaust chambers for reversing the flow of air through the drill passages on turning the valve member, a spring at the smaller end of the taper for holding the valve member up on the same, a sleeve adjustable on the stem at the larger end of the taper and forming an end thrust bearing for the valve member, and a split clamp collar for the sleeve and extending about the same.

4. A reversible drill throttle, comprising a stem having a tapered portion between its ends and having supply and drill passages opening outward through said taper, a tubular valve member with a tapered bore fitting the taper at the stem over the open

- ends of said passages and having inlet and exhaust chambers for reversing the flow of air through the drill passages on turning the valve member, the taper of the stem and that of the bore being complementary and relatively slight so that the end areas of said valve chambers will be substantially the same, a relatively light spring at the smaller end of the taper for holding the valve member up on the same, an end thrust bearing for the valve member at the larger end of the taper, and a grip sleeve on the stem at the spring end thereof and engaged with the valve member for turning the same.
5. A reversible drill throttle, comprising a stem having a tapered portion between its ends and having supply and drill passages opening outward through said taper, a tubular valve member with a tapered bore fitting the taper of the stem over the open ends of said passages and having inlet and exhaust chambers for reversing the flow of air through the drill passages on turning the valve member, the taper of the stem and that of the bore being complementary and relatively slight so that the end areas of said valve chambers will be substantially the same, an end thrust bearing for the valve member at the larger end of the taper, a grip sleeve on the stem at the smaller end of the taper and having a tongue and slot connection with the valve member for turning the same, and a relatively light spring between the grip sleeve and valve member for holding the latter up on the taper of the stem.
6. A reversible drill throttle, comprising a stem with supply and drill passages opening outward through the stem between its ends, a tubular valve member on the stem over the open ends of said passages and having inlet and exhaust chambers for reversing the flow of air through said drill passages on turning the valve member, and a safety lock embracing spaced shoulders on the stem and a pin carried by the valve member and movable into the space between the shoulders for holding the valve member from being turned into reversing position when running the drill forward.
7. A reversible drill throttle, comprising a stem with supply and drill passages opening outward through the stem between its ends, a tubular valve member on the stem over the open ends of said passages and having inlet and exhaust chambers for reversing the flow of air through said drill passages on turning the valve member, said stem having spaced

shoulders, and a key on the valve member and extending into the space between the shoulders to limit the extent of turning of the valve member.

8. A reversible drill throttle, comprising a stem with supply and drill passages opening outward through the stem between its ends, a tubular valve member on the stem over the open ends of said passages and having inlet and exhaust chambers for reversing the flow of air through said drill passages on turning the valve member, said stem having circumferentially spaced shoulders, a ring slidable on the valve member and carrying a pin movable by the ring into the space between shoulders on the stem to prevent turning of the valve member into reversing position while running the drill forward.

9. A reversible drill throttle, comprising a stem with supply and drill passages opening outward through the stem between its ends, a tubular valve member on the stem over the open ends of said passages and having inlet and exhaust chambers for reversing the flow of air through said drill passages on turning the valve member, said stem having spaced shoulders, a key on the valve member and extending into the space between the shoulders to limit the extent of turning of the valve member, and a ring slidable on the valve member and carrying a pin extending into the space between the shoulders through a slot in the valve member to prevent turning of the latter into reversing position while running the drill forward.

10. A reversible drill throttle, comprising a stem with supply and drill passages opening outward through the stem between its ends, a tubular valve member on the stem over the open ends of said passages and having inlet and exhaust chambers for reversing the flow of air through said drill passages on turning the valve member, a ring slidable on the valve member and carrying a pin movable by the ring into the space between shoulders on the stem to prevent turning of the valve member into reversing position while running the drill forward, and a spring band in an internal groove in said ring and frictionally engaging the valve member to hold the ring against accidental lateral movement thereon.

In testimony that I claim the foregoing as my invention, I affix my signature, this 1st day of April, A. D. 1922.

REINHOLD A. NORLING.
